Primary Examiner — Susan Moon Lee(74) *Attorney, Agent, or Firm* — Wayne & Ken, LLC(57) **CLAIM**

The ornamental design for scissors, as shown and described.

DESCRIPTION

FIG. 1 is a front elevation view of scissors showing our new design;

FIG. 2 is a back elevation view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a use state diagram thereof; and,

FIG. 9 is another use state diagram thereof.

The broken lines in the drawing depict environmental subject matter only and form no part of the claimed design.

1 Claim, 9 Drawing Sheets(56)
